UNITED STATES PATENT OFFICE.

MAGDALENE H. McDOWELL, OF LEXINGTON, KENTUCKY.

FIRE-BACK PLATE.

SPECIFICATION forming part of Letters Patent No. 397,742, dated February 12, 1889.

Application filed April 28, 1888. Serial No. 272,162. (No model.)

To all whom it may concern:

Be it known that I, MAGDALENE H. McDOWELL, a citizen of the United States, residing at Lexington, in the county of Fayette 5 and State of Kentucky, have invented certain new and useful Improvements in Fire-Back Plates, of which the following is a specification, reference being had therein to the accompanying drawings.

10 My improvement relates to that class of fire-back plates designed for heating other rooms besides that in which the fire-place is located; and the invention consists in the peculiar construction, arrangement, and combination of parts hereinafter more particularly described, and then definitely pointed out in the claims.

In the accompanying drawings, Figure 1 shows a vertical central transverse section of 20 a fire-place and chimney between two rooms supplied with my invention. Fig. 2 is a similar section of a fire-place and chimney in an outside wall of a house. Fig. 3 is a perspective view of the back-plate detached. Fig. 4 is a 25 modification of the same. Fig. 5 is a perspective view of a chimney having my improvement, with part broken away. Fig. 6 is a plan of the same on the line $\alpha\alpha$, Fig. 7. Fig. 7 is 30 a section on a smaller scale, showing the connection with the upper apartments of the house. Fig. 8 is a section on the line $y\gamma$ of Fig. 7.

Referring now to the details of the drawings by letter, A represents the radiating back-plate set below the chimney-flue H' , and consisting of a casting substantially of the shape shown, and preferably corrugated to add to the stiffness and to give more heating-surface. Heavy boiler-iron may be used, in which case 35 I prefer that it shall be riveted together at C, below which point only one thickness of the iron need extend, if preferred.

Inside the fire-back I provide a partition, P, which is preferably made adjustable by a 40 rack-bar, R, and pinion S, and at D are shown plates built into the brick-work of the chimney and extending across side air-flues, T, into the fire-back, so as to make the air pass into the interior of the fire-back.

45 To utilize the fire-back to the utmost, I sometimes add a hot-air flue, F, as shown in dotted

lines in Figs. 1, 2, and 7, which will carry the heated air in the fire-back to a room above that in which the grate is located. I also in some cases perforate the opposite side of the 55 fire-back at G, so as to allow a portion of the heated air to pass up into the hot-air flue H; or there may be sufficient space left between the side wall and ends of the radiator to allow the hot air to pass into the hot-air flue. 60 This applies more particularly to outside chimneys.

Air may be admitted to the outside of the fire-back through apertures J J or J'.

By moving the partition P in different positions more or less of the heated air may be turned into the different upper rooms; or if the partition is moved close to one of the plates D, most, if not all, of the heated air will be turned into the opposite upper room. By 70 this construction great economy of fuel is obtained, for with one fire four or more rooms may be heated, for the room in which the fire is located will, of course, be heated by direct radiation of the heat from the fire in the grate 75 K, the room at the back of the grate will be heated by radiation from the fire-back, while the rooms above these will be heated by the air that rises through the flues T at either side of the fire-place, as shown in Figs. 5 and 80 7, and also by the heated air that rises through the flue H.

I do not wish to be limited to the exact form of grate shown, as it is evident that any form of fire or heating device may be used, from 85 the old-fashioned andirons and back-log to the most ornate grate or stove.

Although I have described the fire-back as made of cast-iron or boiler-iron, it is evident that any metal may be used, if desired, and in 90 some cases I may make the fire-back of burnished copper, brass, nickel, or other bright metal, which would make the rear side ornamental and be very useful in a narrow hall where fire would be impracticable.

95 What I claim as new is—

1. A double-flue chimney, in combination with a double fire-back arranged between the flues and flattened at top and adapted to form a support for the bricks between the flues, 100 substantially as described.

2. A double fire-back having its lower part

vertical and resting upon the floor, its upper part inclined outward at D and then inclined inward again to form an air-chamber, and having a flat surface above said inwardly-inclined part to form a support for the bricks of the flue, substantially as described.

3. The combination, with a chimney arranged between two chambers and having substantially equal openings into the opposite chambers, of a double radiating fire-back and a heating apparatus, as the grate K, arranged in one of said chambers, whereby one chamber is heated by the grate and the other by direct radiation from the opposite side of the fire-back, substantially as described.

4. The combination, with a chimney arranged between two chambers on the same floor, and having two flues and also two substantially equal openings into the opposite chambers, of a double radiating fire-back and a heating apparatus, as the grate K, arranged in one of said chambers, whereby the two chambers on the same floor and one or more

chambers above may be heated by a single fire, substantially as described.

5. The combination, with a chimney having side air-flues, of a hollow fire-back open at each end and two plates built into the masonry of the flues and extending into the interior of the fire-back, substantially as and for the purpose specified.

6. The combination, with a chimney and a hollow fire-back, of air-flues leading into and out of said fire-back, and a movable partition arranged between the opposite ends of said fire-back, constructed to vary the size of the air-passage through said fire-back, substantially as and for the purpose specified.

In testimony whereof I affix my signature, in presence of two witnesses, this 25th day of April, 1888.

MAGDALENE H. McDOWELL.
